United States Patent Office

Des. 212,584
Patented Nov. 5, 1968

212,584

BOTTLE

James L. Linn, Jr., Maumee, Ohio, assignor to Owens-Illinois, Inc., Toledo, Ohio, a corporation of Ohio

Filed Jan. 26, 1968, Ser. No. 10,332

Term of patent 14 years

(Cl. D9—1)

FIG. 1

The side not shown is the same in appearance as the side shown.

The dominant features of the design reside in the portion shown in full lines.

I claim:

The ornamental design for a bottle, substantially as shown and described.
